[57] CLAIM

The ornamental design for a novelty glove, as shown
and described.

DESCRIPTION

FIG. 1 is a front elevational view of a novelty glove
showing my new design;

FIG. 2 is a rear elevational view thereof;

FIG. 3 is a right side elevational view thereof;

FIG. 4 is a left side elevational view thereof; and,

FIG. 5 is a top plan view thereof.

The broken line showing human element is for illustra-
tive purpose only and forms no part of the claim.

FIG. 1

FIG. 2
